UNITED STATES PATENT OFFICE.

HARVEY BIRCHARD TAYLOR, OF PHILADELPHIA, PENNSYLVANIA.

COMPOSITE SPIRAL CASING.

Application filed April 24, 1922. Serial No. 556,143.

To all whom it may concern:

Be it known that I, HARVEY BIRCHARD TAYLOR, a citizen of the United States, residing at Philadelphia, in the county of Philadelphia and State of Pennsylvania, have invented certain new and useful Improvements in Composite Spiral Casings, of which the following is a specification.

This invention relates to turbines and particularly to volute casings for the flow to the turbine runner. The object of the invention is to provide a casing formed of steel castings and plate steel sections joined together in strong and simple manner. It is also applicable to pumps.

In the accompanying drawings illustrating the invention

Fig. 1 is a plan view of a casing structure.

Fig. 2 is a vertical sectional view on line 2—2 of Fig. 1 the showing of certain sections of the casing being omitted for the sake of clearness of illustration.

Fig. 3 is a similar view on line 3—3 of Fig. 1,

Fig. 3^a is an enlarged detail perspective view showing the interior construction of a portion of the casing.

Fig. 4 is a view similar to Fig. 3 illustrating a modification.

Fig. 5 is a plan view of a modified casing structure.

Fig. 6 is a vertical sectional view on line 6—6 of Fig. 5.

Fig. 7 is a plan view of a further modification.

Fig. 8 is a vertical sectional view on line 8—8 of Fig. 7.

Fig. 8^a is a view similar to Fig. 3^a but showing the modified form of invention disclosed in Figs. 7 and 8.

In the specific embodiment of the invention illustrated in Figs. 1 to 3 the central speed vane ring 5 is formed either as a single casting when shipping restrictions permit, or in four or more sections, (as shown in Fig. 5) having the vanes 6 cast integrally with the upper and lower crowns. The inner portion of this speed ring 5 provides upper and lower flanges 7 for attachment to the central structure supporting the adjustable guide vanes and cover plate, etc., in a manner well known in the art while the outer portion of the speed ring 5 has the outer extensions or flanges 8 finished as gen-

erally conical surfaces 60 for attachment of the plate steel sections of the casing.

The plate steel portion of the casing comprises a series of steel plates 10 of generally segmental form so as to be contained between radial planes of the spiral. At their inner ends these sections 10 are relatively flat, forming conical surfaces, where they are joined to the flanges 8 of speed ring 5 as by riveting or bolting. These plates 10 extend substantially flatwise for a short distance from the point of attachment to the flanges 8 and then curve on substantially circular arcs to the point of attachment to the intermediate outer sections 11 joining the ends of plates 10 and completing each section of the casing. These plates 10 and 11 preferably abut at their edges and are joined together by riveting through the cover plates 12. The plates 11 curve smoothly on arcs merging with the arcs of the plate 10 as indicated at 70 in Fig. 2 and these plates 11 are so formed that that edge 71 of each plate, which may be considered as formed by a radial plane through the turbine axis follows a curve of somewhat greater radius than the radii of curves similarly formed by radial planes but lying farther in on the spiral. In this manner the successive plates along the spiral are made to overlap smoothly. The forward edges 72 of the plates 10 also have a similar curve or bulge to that described in connection with the plates 11 except that this curvature decreases towards the center of the spiral and disappears as indicated approximately at 73 in Fig. 2, before the area of attachment to the central ring 5 is reached.

In order that plates 10 (or 11) may smoothly overlap adjacent plates 10 (or 11), these plates are preferably, though not necessarily, arched or bulged slightly in the direction of the spiral as indicated for example at 75 in Fig. 1. The structure formed by plates 10 and 11 begins preferably at the entrance to the spiral (see section 2—2) and extends for substantially 270° around the central ring 5, the size of the plates and the area enclosed, of course, gradually decreasing as the spiral converges.

The throat section 14 at the very beginning and end of the spiral is built of cast steel formed for attachment to the plate steel sections around it. This section 14 comprises two portions 15 and 19 each of which forms

a water guiding surface. The portion 15 conforms to the general cylindrical contour of the entrance passage of the spiral and is flanged at 16 for attachment to the entrance 5 plate sections 17 and 18. The portion 19 forms a continuation of the converging spiral passage and is flanged at 24 for attachment to the adjacent spiral section 25. The portions 15 and 19 form continuations of the 10 surfaces of a separating vane 20 of the speed ring 5. Flanges 16 and 24 continue above and below the speed ring and are joined by curved portions 61 which are bolted to the speed ring at 22. Horizontal and vertical 15 web members 21 forming a box section connect the body portions 15 and 19 to the throat section 14.

In Fig. 4 a modified form of throat section 14' is shown adapted to be bolted to extensions 26 of the ring flanges 8 with the 20 terminal section 25 of the volute extending within and underneath these extensions 26 and the edge flange of the throat section 14', as shown in Fig. 4.

In the modified form of casing shown in Fig. 5 the smaller portions of the volute are formed by cast sections 30, 31 instead 25 of the plate sections 10, 11. This will often be advantageous since these portions are of 30 much smaller weight than the large sections of the volute and the form of these smaller sections (Figs. 3 and 4) involves more rapid curvature than the larger sections. The bending or bulging required in the plates of 35 the large sections is comparatively slight and the plate structure is lighter and less expensive. Toward the smaller portions of the volute however the saving in weight decreases and the rather sharp curvatures assumed by the sections are best provided by 40 cast sections so that in many cases the cast portion of the composite casing will include to greater or less extent the end volute sections.

In the specific embodiment of this modification shown in Figs. 5 and 6 the central speed ring 35 is formed in four parts bolted together and each carrying its quota of cast stay vanes. Portions of this speed ring are 45 provided with flanges 8' for attachment of plate sections 10, and the remainder of the ring is provided with flanges 38 for bolting on of cast sections 14', 30 and 31, which sections are flanged and bolted together. The 50 end of the last plate section 10, is received in the entrance of the cast section 31 as shown at 39 and is riveted thereto.

In some installations it may also be 55 advantageous to substitute for the entrance sections 17, 17' cast sections 37, 37' bolted to the throat section 14' and to each other to complete the intake. This will give a line of 60 cast sections 37', 37, 14', 30 and 31 bolted together and riveted to the plate portion of 65 the volute casing at each end.

In the casing of Figs. 7, 8 and 8^a the speed vane ring is provided in part by the inner portions of radial cast sections and in part by a series of separate inner sections all of said sections containing stay vanes cast 70 integrally with them. The throat section 40 and the volute sections 41 and 42 at the small end of the casing are flanged and bolted together and have their inner portions forming part of the speed ring as indicated by the 75 stay vanes 46 cast integrally with said sections. The remainder of the speed ring is formed by the series of inner cast sections 43 bolted together and each section carrying a corresponding stay vane 47 cast integrally 80 with it. The inner portions of the sections 40, 41, 42 and 43 are provided with the circular flanges 48 for the attachment of the cover parts, etc. The outer portions of the cast sections 43 are machined with plane surfaces for attachment of the outer plate sections 50 and 51 which are curved and bulged to successively fit within each other to complete the casing, the larger sections of the 85 plate portion of the casing are formed by a 90 plurality of plates 51, 52 longitudinally joined together along staggered joints 53 and the entrance section formed by plates 54, 54' is riveted to the flanges 58 of the throat section 40. In the casing shown in Fig. 7 each 95 central cast section 43 has its outer edge 58 to which the plates 51 are riveted, planed as a straight plane surface. In this figure the separate speed ring sections do not extend completely around the circumference but a 100 gap is left where sections 41, 42 intervene. Section 40 contains a longitudinal plane surface where the plate steel barrel 54 of the intake section is riveted to it.

This plate formation of the walls of the 105 volute passage saves metal and decreases the weight and size for transportation. The bulged formation is provided by simply pressing or bending the flat metal sections to desired shape previous to assembly and it is to be noted that this bulging to provide for overlapping of the successive sections is different in form from the exact spiral contour, it being intermediate between the full spiral and straight line. Successive joints 110 between sections 10 and 11 and 51, 52 are staggered with relation to each other, as shown, for strength and ease of construction. Each plate metal section is joined at its inner throat portion to a solid steel 115 casting carrying an integral vane structure so that the whole is bound together in a strong unitary structure. The relatively complicated throat formation at the wedge or baffle between the entrance and termination 120 of the spiral is formed by a solid steel casting overlapping and bolted to the central ring casting, these two castings forming a rigid central skeleton for the surrounding plate structure. This casing is 125 130

adapted for very large sizes of units and has been designed for use in a 70,000 H. P. turbine.

I claim:

5 1. In a spiral casing the combination with a central structure of cast metal comprising a series of stay vanes cast in said structure, of a surrounding volute casing body composed partly of cast metal and partly of plate metal.

10 2. In a spiral casing the combination with a central speed ring having stay vanes cast integrally therewith, of a surrounding volute casing body composed partly of cast metal and partly of plate metal.

15 3. In a spiral casing the combination with a central structure of cast metal comprising separate sections connected together and having a series of stay vanes cast in said structure, of a surrounding volute casing body composed partly of cast metal and partly of plate metal.

20 4. In a spiral casing the combination with a central structure of cast metal and a throat section of cast metal bolted to said central structure, of a volute casing body comprising a series of plate metal sections fastened to said central structure.

25 5. In a spiral casing the combination with a central structure of cast metal and a throat section of cast metal bolted to said central structure, of a volute casing body comprising a series of plate metal and cast metal sections fastened to said central structure.

30 6. In a spiral casing the combination with a central structure of cast metal comprising a series of stay vanes cast in said structure, of a surrounding volute casing body composed partly of cast metal and partly of plate metal sections, each section comprising a plate curved transversely of the spiral and bulged from edge to edge so that successive sections smoothly overlap one over the other.

35 7. In a spiral casing the combination with a central structure of cast metal comprising separate sections connected together and having a series of stay vanes cast in said structure, of a surrounding volute casing body composed partly of cast metal and partly of plate metal sections, each section comprising a plate curved transversely of the spiral and bulged from edge to edge so that successive sections smoothly overlap one over the other.

40 8. In a spiral casing the combination with a central cast stay vane ring, of a surrounding volute casing body comprising at least one cast section of volute form, the remainder of the volute being of plate metal sections.

45 9. A volute casing body comprising a plurality of cast metal sections separated on transverse planes cutting across the volute from the inner to the outer periphery, flange

joints connecting said sections, and plate metal sections connected together to form a portion of said body connected to one of said cast sections.

50 10. In a spiral casing the combination with a central speed ring, of a throat casting bolted to said ring between the beginning and end of said spiral and a plurality of plate metal sections extending around said speed ring and throat casting and connected thereto.

55 11. In a spiral casing the combination with a central speed ring, of a plurality of plate metal sections connected thereto, and a throat casting bolted to said speed ring and intervening between the plate metal sections of the beginning and end of the spiral.

60 12. In a spiral casing, a section bounded by transverse planes cutting across the spiral from the inner to the outer periphery, the inner portion of said section being of cast metal containing a stay vane or vanes cast integrally therewith, and the outer portion of said section being of plate metal connected to said inner portion.

65 13. In a spiral casing, a section bounded by transverse planes cutting across the spiral from the inner to the outer periphery, the inner portion of said section being of cast metal containing a stay vane or vanes cast integrally therewith, and the outer portion of said section being of plate metal connected to a plane surface on said inner portion.

70 14. In a spiral casing, a section bounded by transverse planes cutting across the spiral from the inner to the outer periphery, the inner portion of said section being of cast metal containing a stay vane or vanes cast integrally therewith, and the outer portion of said section being of plate metal connected to said inner portion by a riveted joint.

75 15. In a spiral casing, a section bounded by transverse planes cutting across the spiral from the inner to the outer periphery, the inner portion of said section being of cast metal containing a stay vane or vanes cast integrally therewith, and the outer portion of said section being of plate metal connected to said inner portion by riveting the plate metal to a plane surface on said inner portion.

80 16. In a spiral casing the combination with a central structure of cast metal and a throat section of cast metal bolted to said central structure, of a volute casing body comprising a series of plate metal sections fastened to said central structure and overlapping one another.

85 17. A volute casing body comprising a plurality of cast metal sections separated by transverse planes cutting across the volute from the inner to the outer periphery, flange joints connecting said sections, and metal

plate sections overlapping one another and connected together to form a portion of said body connected to one of said cast sections.

18. A spiral casing comprising connected sections bounded by transverse surfaces cutting across the spiral from the inner to the outer periphery, the inner portions of said sections being of cast metal and the outer portions being of plate metal connected to

10 said inner portions, said plate metal sec-

tions being connected to one another by overlapping joints.

19. A spiral casing for a hydraulic turbine or pump extending circumferentially around said turbine or pump, comprising a 15 portion of cast metal subtending a part of the circumference and an adjoining sheet metal portion subtending another part of the circumference.

HARVEY BIRCHARD TAYLOR.
